(57) **CLAIM**

The ornamental design for a housing for game controller, as shown and described.

DESCRIPTION

FIG. 1 is a perspective view of front, bottom and right side of a housing for game controller showing our new design; FIG. 2 is a perspective view of a rear, top and left side thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof; and,

FIG. 8 is a bottom plan view thereof.

The broken lines shown in the drawings depict portions of the housing for game controller that form no part of the claimed design.

1 Claim, 6 Drawing Sheets
